UNITED STATES PATENT OFFICE.

HENRY A. FRAMBURG, OF BERWYN, ILLINOIS.

LAMP-SOCKET STRUCTURE.

1,335,828.

Specification of Letters Patent.

Patented Apr. 6, 1920.

Application filed May 7, 1919. Serial No. 295,420.

To all whom it may concern:

Be it known that I, HENRY A. FRAMBURG, a citizen of the United States, and a resident of Berwyn, in the county of Cook, 5 State of Illinois, have invented certain new and useful Improvements in Lamp-Socket Structures, of which the following is a specification.

My invention relates to lamp socket structures and covers improved construction which is particularly useful in connection with lamp shade holders which surround the socket structure.

My invention is particularly useful in 15 connection with such shade holder structures as are disclosed in my co-pending application executed of even date herewith. The object of my invention is to provide a container structure for the lamp supporting 20 socket comprising separable parts, one of the parts forming adequate support for a shade holder and the other part being applicable to said shade holder part to clamp the lamp socket rigidly in place. This construction enables the lamp socket terminals 25 to be readily and easily accessible from the side after the shade parts have been removed from the holder.

The various features of my invention are 30 clearly disclosed on the accompanying drawing in which—

Figure 1 is a side elevational view of my improved socket structure showing a shade holder thereon,

Fig. 2 is a vertical diametral sectional view of the socket container showing the 35 socket therein,

Fig. 3 is a lower end view of the stationary member of the socket container and

Fig. 4 is a lower end view of the entire 40 socket structure.

Referring to the drawing the upper or stationary member 5 of the socket closure or housing is a cylindrical block of porcelain or other insulating material and has the pocket 6 therein from which the axial passageway 7 leads. A plate 8 is secured against the top of the member 5 by screws 5 or otherwise and has the flange 9 extending therefrom which is both internally and externally threaded. The internal threads receive a conduit pipe 10 and the external threads serve to receive a nut 11 which in practice secures a shade part to the 55 socket structure. Secured in the member 5 at opposite sides thereof are the arms 12

and 13 which are preferably of springy sheet metal and secured by means of bolts 14. The arms 12 and 13 extend from the member 5 in axial direction and at their outer ends have the inwardly extending projections 15 and 16 which are readily formed by deflecting the sheet metal. These arms receive between them the head 17 of the socket, this head having the depressions 65 or pockets 18 and 19 for receiving the extensions 15 and 16 respectively. The cord 20 extends through the conduit 10 and the conductors 21 and 22 are connected with the socket terminals 23 and 24 respectively, of 70 the tip and sleeve members 25 and 26 of the socket.

The separable member for the socket inclosing structure is in the form of a sleeve 27 whose outer end is of reduced diameter 75 and provided with internal threads 28 for receiving the threaded sleeve member 26 of the socket. When the socket structure is first installed, its member 5 is secured to the conduit pipe 10. The socket is then inserted between the arms 12 and 13 which pass along the sides of the socket's head and finally engage with their projections 15 and 16 in the pockets 18 and 19. The ends of the conductor leads 21 and 22 are 80 then secured to the socket terminals 23 and 24. The member 27 is now applied by screwing it on to the sleeve terminal 26 of the socket, the inner end of the member 27 receiving the head of the socket and engaging with its inner side against the outer-sides of the arms 12 and 13. Such engagement of the member 27 with the arms 85 securely locks these arms with their projections in the pockets and when the shoulders 29 and 30 of the member 27 and the socket come into engagement, the socket and the member 27 will be securely locked together and the socket and the member securely clamp between them the arms 12 and 13 and hold these arms rigidly in place so that a 90 very rigid socket structure is formed. The arms 12 and 13 thus support the socket and the closure member 27.

To facilitate guidance of the arm projections 18 and 19 into the pockets of the socket head, the socket head is provided with guide ridges 31 which engage in guide grooves 32 formed in the member 5. If desired the inner surface of the inner end of the member 27 may be roughened or provided with ridges or corrugations 33 which afford fric- 105 110

tional and detent engagement of the member 27 with the arms 12 and 13, this frictional or detent engagement serving to lock the member 27 against loosening when the 5 shoulders 29 and 30 have not been drawn into tight engagement.

In Fig. 1, I have shown shade holder supporting arms 34 extending downwardly alongside of the socket structure from the 10 top plate 8, the lower ends of these arms being bent to provide inner shade engaging lugs 35 and outer pockets 36. As disclosed in my co-pending application referred to, these outer pockets support a split ring 37 15 whose one end is connected with the end of a lever 38 and whose other end is connected to the intermediate part of the lever in such a manner that swing of the lever in one direction or the other will cause either expansion 20 or contraction of the ring to release a shade or to draw the fingers 34 into engagement therewith. After application of a shade a protecting cap for the socket structure and holder is usually provided as shown 25 in my co-pending application referred to. With the improved construction of the socket structure here disclosed the structure can be readily opened to give ready access to the socket terminals when the shade and 30 protecting cap have been removed. As soon as the member 27 has been unscrewed from the socket, the socket terminals are accessible and when these terminals have been 35 opened the socket can be readily entirely withdrawn from its supporting arms 12 and 13. When the socket is slipped into the member 5 the spring arms 12 and 13 will temporarily hold it in place until the sleeve member 27 is screwed on to the socket sleeve 40 end and then the arms will be securely clamped against the socket head and the member 27 will be locked in place.

I do not desire to be limited to the exact construction and arrangement shown and 45 described as changes are possible which would still come within the scope of my invention.

I claim as follows:

1. In a socket structure, the combination 50 of a top closure member, arms extending downwardly from said member, a socket member having a head received between said arms and having a threaded sleeve terminal, and a lower closure member for receiving 55 said socket and having a threaded end for engaging said threaded sleeve, said arms being clamped between said socket head and said lower closure member.

2. A socket structure comprising a top 60 member having an entrance for current conductors, arms extending from said top member, a socket member comprising a head and a threaded sleeve terminal, said arms hav-

ing projections and said head having depressions for receiving said projections, 65 and a lower closure member in the form of a tube having a threaded end for receiving said socket sleeve terminal, the inner end of said lower closure member receiving said socket head and clamping said arms against 70 said head.

3. A socket structure comprising a top closure member, spring arms extending from said closure member, a socket member having a head and a threaded terminal sleeve, 75 said head being received between said arms, and an annular closure member having threaded engagement with said sleeve and adapted to surround said head to clamp said arms thereto.

4. A socket structure comprising a top closure member, spring arms extending downwardly from said member, a socket member having a head and a threaded terminal sleeve, said arms having projections 85 and said head having depressions for receiving said projections, and an annular closure member having threaded engagement with said terminal sleeve and surrounding said head whereby said arms are 90 securely clamped between said head and member thus rigidly secured to said arms.

5. A socket structure comprising a top closure member, sheet metal arms extending 95 from said closure member and having projections at their ends, a socket member having a head and a threaded terminal sleeve, said head having depressions for receiving said arm projections, a ring for surrounding said head to clamp said arms securely thereto, and a threaded extension on said ring having threaded engagement with said terminal sleeve whereby said ring may be applied in arm clamping position.

6. A socket structure comprising a supporting member, arms extending therefrom, a socket member having a head and a threaded sleeve, said head being received between said arms, a ring having threaded engagement with said threaded sleeve, and a flange on said ring for receiving the socket head to clamp said arms thereto.

7. A socket structure comprising a supporting member, arms extending from said supporting member, a socket member having a head and a threaded sleeve, said arms and head having frictional projection and depression engagement, a ring having threaded engagement with said sleeve, and a flange on said ring for surrounding the arms on said supporting member and clamping them securely against the head.

In witness whereof, I hereunto subscribe my name this 2nd day of May A. D., 1919. 125
HENRY A. FRAMBURG.
